UNITED STATES PATENT OFFICE

168,920

HAT

Edward Wittcoff, University City, Mo., assignor to
Caradine Hat Company, St. Louis, Mo., a corporation of Missouri

Application March 19, 1952, Serial No. 18,956

Term of patent 14 years

(CL. D3—13)

To all whom it may concern:

Be it known that I, Edward Wittcoff, a citizen of the United States, residing in University City, State of Missouri, have invented a new, original, and ornamental Design for a Hat, of which the following is a specification, reference being had to the accompanying drawing forming a part thereof.

Fig. 1 is a top plan view of a hat embodying my new design;

Fig. 2 is a side elevational view thereof;

Fig. 3 is a side elevational view showing the other side thereof; and

Fig. 4 is an end elevational view thereof.

The stippling on the drawing indicates contrasting color.

I claim:

The ornamental design for a hat, substantially as shown and described.

EDWARD WITTCOFF.
